UNITED STATES PATENT OFFICE.

JOHN N. CARTER, OF TRENTON, NEW JERSEY, ASSIGNOR TO BERGOUGNAN RUBBER CORPORATION, OF WILMINGTON, DELAWARE, A CORPORATION OF DELAWARE.

DESIGN FOR A NONSKID TIRE.

Application filed January 12, 1922. Serial No. 186. Term of patent 14 years.

To all whom it may concern:

Be it known that I, JOHN N. CARTER, a citizen of the United States, residing at Trenton, in the county of Mercer and State of New Jersey, have invented a new, original, and ornamental Design for Nonskid Tires, of which the following is a specification, reference being had to the accompanying drawing, forming a part thereof.

Figure 1 is a plan view of the tread surface of a tire, showing my new design, and Figure 2 is a sectional view on line 2—2 of Figure 1.

I claim:

The ornamental design for a nonskid tire, as shown.

JOHN N. CARTER.
